Primary Examiner — Steven J Czyz(74) *Attorney, Agent, or Firm* — Sarah J. Rhoades(57) **CLAIM**

The ornamental design for a tarp compressing device, as shown and described.

DESCRIPTION

FIG. 1 is a top perspective view of a tarp compressing device, shown with the compression element disengaged from the receiving element;

FIG. 2 is a front view thereof;

FIG. 3 is a top view thereof;

FIG. 4 is a bottom view thereof;

FIG. 5 is a rear view thereof;

FIG. 6 is a right side view thereof;

FIG. 7 is a left side view thereof;

FIG. 8 is a front view of the tarp compressing device, shown with environment and with the compression element engaged with the receiving element;

FIG. 9 is a top view thereof;

FIG. 10 is a right side view thereof; and,

FIG. 11 is a left side view thereof.

The broken lines depict portions of the article and environment that form no part of the claimed design.

1 Claim, 5 Drawing Sheets(56)
